UNITED STATES PATENT OFFICE.

JOSEPH H. JONES, OF WINTHROP, MASSACHUSETTS, ASSIGNOR OF ONE-HALF TO
ROBERT BURGESS, OF NEWTON CENTER, MASSACHUSETTS.

CAP-SPINNING FRAME.

1,385,078.

Specification of Letters Patent. Patented July 19, 1921.

Application filed November 10, 1919. Serial No. 336,897.

To all whom it may concern:

Be it known that I, JOSEPH H. JONES, a citizen of the United States, residing at Winthrop, in the county of Suffolk, State 5 of Massachusetts, have invented a certain new and useful Improvement in Cap-Spinning Frames, of which the following is a specification, reference being had therein to the accompanying drawings.

10 The invention relates to cap-spinning devices of the class in which a cap and the spindle or bobbin with which it co-operates revolve in unison.

It provides in a novel manner for controlling a cap vertically, throughout the spinning process, and during the relative traversing movements, between it and its co-operating spindle or bobbin, by which the twisted yarn in being wound upon the spindle or bobbin is distributed thereon, so as 20 to be built up into the required form of yarn-mass.

It consists in a simplified and improved construction and combination of a cap and its controlling means, by which wear of the parts is reduced and practically eliminated, and better results are secured in the spinning.

The drawings show an illustrative embodiment of the invention, which is also the preferred form of embodiment.

Figure 1 of the drawings is a view of certain parts of a spinning frame, illustrating the said embodiment, the said parts being shown mainly in front elevation but with one of the caps in transverse section in a vertical plane.

Fig. 2 is a view looking from the right hand side in Fig. 1, with the rails in vertical cross section.

At 1, Fig. 2, is a portion of a thread-board having hinged thereto at 2, in usual manner, a series of blocks 3 carrying the guides 4 for the yarns between the front rolls and the 45 twisting devices. At 5 is a spindle-rail having mounted thereon in usual manner bearing-supports 6 of spinning-spindles 7, in this instance of the well-known sleeve-whirl type, driven by means of bands 8 encircling the whirls 7^a. At 9 are quills or bobbins mounted upon the spindle-blades. At 10 are revolving caps co-operating with the said quills or bobbins. At 11 (Fig. 2) is one of the cap-controlling wheels, it coacting with the adjacent cap in the manner explained hereinafter; at 12 is a mounting for the

wheel 11; and at 13 is a rail supporting the mountings of the series of wheels 11 co-operating with the series of caps 10.

The caps 10 have the holes through their heads bushed as at 14, Fig. 1. The central openings of the bushings are so proportioned that the bushings have a close but easy sliding fit upon the blades or barrels of the spinning elements to which the caps are applied, such elements being in this instance the quills or bobbins 9. The said sliding fit permits the caps to gravitate downward upon the said blades or barrels until they are supported vertically through engagement with the wheels 11, and also permits the traverse movements of the caps up and down upon the said blades or barrels which are required to take place for the distribution of the twisted yarn upon such blades or barrels in being wound thereupon. The caps are caused to revolve through light frictional contact between the peripheries of the said blades or barrels and the inner surfaces of the said bushings.

Referring now to the features of the invention:

Important characteristics of the invention that will be apparent from Fig. 2 of the drawings are, first, that during operation 85 the contact that takes place between a revolving cap 10 and its controlling wheel 11 is purely a rolling peripheral contact without any sliding contact and resulting friction and wear such as are found in the 90 case of earlier devices; and, second, that the cap is controlled vertically by the said peripheral contact. The principle of construction that is utilized in securing the said rolling peripheral contact, accompanied by the 95 said vertical control of the cap, consists in making one of the two elements in question cone-shaped, and arranging it so that the longitudinal line of its surface which contains the point at which contact with the 100 other member takes place, inclines upwardly toward the prolongation of the axis of the wheel. In simple terms, the essential relations of the cone-shaped member and coacting wheel are such that a peripheral portion 105 of the cap overhangs a peripheral portion of the wheel, but without vertical contact between any portion of the cap and a horizontal surface of the wheel. The gravitating tendency of the cap operates to keep 110 the overhanging peripheral portion of the cap in contact with the peripheral wheel.

portion that it overhangs. The resting of the said overhanging portion of the cap upon the portion of the wheel with which the peripheral contact occurs provides for the support of the cap vertically by means of the wheel, and in obvious manner secures the control of the cap by the wheel in the traverse movements by which the distribution of the twisted yarn is effected in building up the yarn mass.

In the operation of a spinning frame in which the invention is applied, the said traverse movements may be communicated to either the rail 13 or the spindle-rail 5, as may be preferred, usually the former. In a rising movement of rail 13 and wheel 11, for example, the contact of the periphery of the wheel 11 with the upwardly flaring periphery of the cap shown in the drawings will operate to move the cap 10 upward along the blade or barrel of the quill or bobbin 9, while in the descending movement of said rail the cap will accompany the wheel downward, its periphery keeping practically in touch with that of the wheel.

The gravitating tendency of the cap, in conjunction with the conical shape of one of the two members and the described overhanging of the cap-periphery with relation to the wheel-periphery, have the effect of rendering the cap automatic in finding its proper working relations with the wheel 11 and keeping in substantially continuous contact therewith. Hence the control of the position of the cap is maintained continuously, and the proper distribution of the twisted yarn upon the quill 9 is insured.

Delicate adjustment of the spindle and its cap, and of the wheel 11 is not needed for the purpose of insuring any exact distance between the axes of the two, being rendered unnecessary by the automatic action of the gravitating cap in seeking and maintaining the required peripheral contact with the wheel 11; consequently, any slight variation forwardly or rearwardly in the setting of the spindle mountings 6 in the holes 5^a in rail 5 occupied by them is compensated for automatically by the said action. Therefore by independent adjustment of the respective wheels 11 is unnecessary.

As will be apparent from Fig. 2, the yarn α in revolving around the axis of the spindle, quill, or bobbin, and cap, will pass easily between the periphery of the cap 10 and that of the wheel 11. There is no tendency to detain the yarn between the cap and wheel, and there is no injurious action upon the

yarn tending to weaken or break the same, or to affect its uniformity.

As will be apparent, also, from Fig. 2, the wheel 11 will act usefully in restraining ballooning.

Various modifications may be made in the construction without involving a departure from the invention.

One effect of the engagement of the conical periphery of the cap with the periphery of the wheel is a tendency to press the cap bodily away from the wheel, and to tilt the cap slightly in a vertical plane. The next result of this tendency is a closer engagement of the bushing 14 of the cap with the blade or barrel of the spinning element 9, operating to insure rotation of the cap in unison with said element, which is particularly advantageous in starting at the spinning-frame after a stoppage.

What is claimed as the invention is,—

1. In spinning devices of the revolving cap class, the combination with a revolving spinning element, of a cap mounted upon the blade or barrel of said element, revolved thereby and movable longitudinally thereof, and a wheel for said cap controlling the latter in the traverse movements, said cap and wheel having purely rolling peripheral contact between the tapering periphery of one thereof and the periphery of the other, one of them being cone-shaped, and with a peripheral portion of the cap overhanging a peripheral portion of the wheel.

2. In cap-spinning devices, in combination, a revolving vertically gravitating cap, and a controlling wheel therefor, one of said elements cone-shaped, with a peripheral portion of the cap overhanging the wheel, and with purely rolling peripheral contact between the tapering periphery of one of said elements and the periphery of the other thereof.

3. In cap-spinning devices of the revolving cap class, the combination with a revolving spinning element of a cone-shaped upwardly flaring cap mounted upon the blade or barrel of said element, revolved thereby, and movable longitudinally thereof, and a controlling wheel for the said cap, in purely rolling peripheral contact with the latter.

In testimony whereof I affix my signature in presence of two witnesses.

JOSEPH H. JONES.
